UNITED STATES PATENT OFFICE

CHARLES F. PYM, OF BEVERLY, MASSACHUSETTS, ASSIGNOR, BY MESNE ASSIGNMENTS, TO THE LITTLEWAY PROCESS COMPANY, OF BOSTON, MASSACHUSETTS, A CORPORATION OF MASSACHUSETTS

MEANS FOR HOLDING SHOE UPPERS IN LASTED POSITION

Application filed January 21, 1930. Serial No. 422,444.

This invention relates to means for use in the manufacture of shoes for holding the uppers in lasted position, and more particularly to means adapted for use temporarily in holding or pressing engagement with a portion of an upper on the bottom of a shoe to maintain the upper in lasted position until conditions are such that it will remain in that position without the aid of extraneous fastening or holding means, as a result, for example, of the hardening of cement between the upper and an insole or, as applied to box toes, the hardening of the box toe stiffening material. The invention is applicable to the manufacture of shoes of different kinds, including those in which the margin of the upper is lasted in generally parallel relation to the bottom of the last over the outer face of an insole, and also those in which it is lasted in the angle adjacent to a lip or rib on the insole, as in shoes of the welt type, and accordingly the invention is herein illustrated by reference to the manufacture of these two kinds of shoes. The invention is further illustrated by reference to the lasting of the toe ends of shoes, although it is to be understood that it is not thus limited in its applicability.

An object of the invention, in general, is to provide means of the above-mentioned character so constructed as to adapt it to be readily applied to a shoe and removed therefrom, and also of such construction as to render it especially effective in its application of pressure to the upper in a location at or near the edge of the shoe bottom. For the purpose in view the invention accordingly provides novel upper-holding or pressing means comprising, as herein illustrated, a device having a portion formed to engage the upper continuously along the edge of that portion of the shoe bottom where the device is located and to press it toward the bottom face of the last and another portion arranged to extend farther inwardly over the shoe bottom than its upper-pressing portion for use in fastening the device to the shoe and offset relatively to the upper-pressing portion to position it in spaced relation to the shoe bottom. For use in the manu-

facture of shoes of that type in which the upper is lasted over the outer face of the insole in generally parallel relation to the last bottom, the upper-pressing portion of the device herein shown is so formed as to apply its pressure only at a distance from the edge of the upper, so that the portion of the upper adjacent to its edge, where the wrinkles resulting from the gathering of its margin around the toe are most prominent, will not tend to restrict the amount of pressure applied by the device near the edge of the shoe bottom and will, moreover, be left in a more or less upstanding condition convenient for the later upper-trimming operation. On a shoe of this type the offset relation of the inwardly extending portion of the device affords room for the wrinkled margin of the upper while also insuring, in general, against any possibility of restriction of the amount of pressure applied to the upper by reason of engagement of the device with a portion of the shoe located farther inwardly from the edge of the shoe bottom than that portion where the pressure is applied. In the use of the device on shoes of that type in which the insole is provided with a lip or rib (hereinafter referred to as a lip) against which the upper is lasted, the upper-pressing portion of the device serves to press the upper upon the feather of the insole and also to conform it to the angle between the feather and the lip, while the offset relation of the inwardly extending portion of the device permits the latter to clear the lip and to extend inwardly beyond it. For use in lasting the toes of shoes, the device herein shown comprises a rigid plate having a marginal upper-pressing portion curved in general similarity to the contour of the edge of the shoe bottom around the toe; and in accordance with a further important characteristic, the construction is such as to provide surfaces adapted to be engaged by the toe wipers of a lasting machine for pressing the device both inwardly over the shoe bottom lengthwise of the shoe and in a direction toward the bottom face of the last preparatory to the fastening of the device to the shoe.

While it is contemplated that the device may be held on the shoe in various ways, it is herein shown as provided with a plurality of holes in its inwardly extending portion 5 through which fastenings, such as tacks, are driven into the shoe bottom to clamp the device in pressure-applying relation to the upper. To facilitate the driving of the tacks depressions may be formed, as illustrated, 10 adjacent to the tack holes to receive and position the nozzle of a tack-driving tool, such as a hand tacker, these depressions also permitting the tacks to be driven farther into the shoe or last and therefore contributing 15 to the security with which the device is fastened to the shoe. It will accordingly be evident that the device may be quickly and easily fastened to the shoe, and also that it may be readily removed by inserting a suitable 20 tool between its inwardly extending portion and the bottom of the shoe and prying it away from the shoe bottom.

The novel features of the invention will now be more particularly described by reference 25 to the accompanying drawings and thereafter pointed out in the claims.

In the drawings,

Fig. 1 is a perspective view illustrating how the upper-holding device provided by the invention may be applied to the toe portion of a shoe by the aid of the toe-embracing wipers of a bed-lasting machine, the shoe illustrated being one of that type in which the upper is lasted over the outer face of an insole in generally parallel relation to the last bottom;

Fig. 2 is a section on the line II—II of Fig. 1, illustrating more clearly the construction of the device and its relation to the shoe and the wipers, the toe band of the lasting machine 40 being omitted;

Fig. 3 is a section on the line III—III of Fig. 2;

Fig. 4 is a perspective view of the upper-holding device detached; and

Fig. 5 is a view similar to Fig. 2, illustrating the application of the device to a shoe having an insole provided with a lip against which the upper is lasted.

The upper-holding or pressing device herein shown comprises a rigid metal plate having a marginal portion 10 curved in general similarity to the curvature of the edge of the toe end portion of the bottom of a shoe and formed to apply to the upper continuously 55 around the toe end of the shoe bottom pressure in a direction toward the bottom face of the last to press the upper upon an insole on the last. The width of the marginal portion 10 of the plate is such that in operating on 60 shoes of that type in which the upper is lasted over the insole in generally parallel relation to the bottom of the last, as illustrated in Figs. 1, 2 and 3, it applies its pressure over an area extending a substantial distance inwardly 65 from the edge of the shoe bottom to maintain

the upper in a substantially flat condition and also, if cement is used to fasten the upper to the insole, to insure an extended and effective bond between the upper and the insole. The construction, however, is preferably such that the pressure is applied only in a location at a substantial distance from the edge of the upper, so that portions of the margin of the upper adjacent to its edge, where the wrinkles produced by the gathering of the margin around the toe are most prominent, will not tend to restrict the amount of pressure applied near the edge of the shoe bottom and will also be left in a more or less upstanding condition 70 convenient for the later upper-trimming operation. In operating upon shoes of that type in which the insole is provided with a lip *a* (Fig. 5) against which the upper is lasted, the marginal portion 10 of the plate serves to press the upper upon the margin or feather of the insole and also to maintain it in close conformity to the angle between the feather and the lip.

For use in fastening the upper-holding device or plate to the shoe, it is provided, in the construction shown, with another portion 12 arranged to extend farther inwardly over the shoe bottom than its upper-pressing portion and offset relatively to the latter to position it in spaced relation to the shoe bottom. In operating on shoes of the type illustrated in Figs. 1, 2 and 3 this affords room between the plate and the insole for the wrinkled margin of the upper extending inwardly beyond the upper-pressing portion 10 of the plate, while also insuring, in general, against restriction of the amount of pressure applied near the edge of the insole by possible engagement of the plate with another portion of the shoe bottom. In the use of the device on shoes of the type illustrated in Fig. 5 the offset relation of the inwardly extending portion 12 permits it to clear the lip of the insole while extending inwardly beyond it.

While it is considered that a device having characteristics such as thus far described may be held in pressure-applying position in various ways, its inwardly extending portion 12 is herein shown as provided with a plurality of openings or holes 14 to receive tacks driven through the insole and into the last to clamp the device by their heads in pressure-applying relation to the upper. As illustrated, the holes 14 are arranged in a row extending around the toe end of the shoe bottom, but located farther inwardly from the edge of the shoe bottom than the upper-pressing portion of the device and farther inwardly than the lip of the insole in operating on shoes of the type shown in Fig. 5. It will be understood that tacks may or may not be driven in all the holes provided, and also that the number or arrangement of the holes may be varied. To facilitate the driving of the tacks by the use of a tack-driving tool, such as a

hand tacker of the type commonly used in lasting, there are provided depressions 16 in the plate adjacent to the holes 14 to receive and position the end of the nozzle of the tacker. This construction also permits the tacks to be driven farther into the last and therefore contributes to the security with which the device is fastened to the shoe. It will be understood that the depressions 16 may be omitted in case, for example, it is desired to use a hammer for driving the tacks.

In accordance with a further characteristic, the upper-holding device herein shown is so constructed as to adapt it to be readily 15 pressed against the shoe and held until it is fastened to the shoe by means of the toe-embracing wipers of a bed-lasting machine whereby the upper is wiped inwardly over the insole before the device is applied to the 20 shoe. In Fig. 1 there is shown a portion of a bed-lasting machine of a well known type, features of which are disclosed, for example, in Letters Patent No. 1,284,870 granted on

November 12, 1918 upon an application of 25 Matthias Brock. It will be understood that such a machine includes toe-embracing wipers 20 which are advanced lengthwise of the shoe and closed inwardly over the sides of the toe by a hand lever and are also moved heightwise of the shoe by a treadle in a well-known manner. It will be seen that the marginal portion 10 of the device presents an upper surface adapted to be engaged by the wipers to press the device down upon the shoe bottom, and at the junction of this portion of 30 the device with the inwardly extending portion 12 there is further provided a shoulder or surface 22 (Fig. 4) adapted to be engaged by the edges of the wipers to force the device 35 inwardly over the shoe bottom in a direction lengthwise of the shoe to insure that the upper will be drawn tightly over the edge of the insole and also, in operating on shoes of the type illustrated in Fig. 5, that it will 40 be pressed closely against the lip of the insole. It will be understood that the upper will first be wiped inwardly over the insole by the wipers to shape its marginal portion preliminarily in lasted relation to the insole, after 45 which the wipers will be retracted and the upper-holding device applied to the shoe.

The wipers will thereafter be again advanced and closed in engagement with the upper-holding device and will also be pressed down- 50 wardly toward the shoe bottom to force the device firmly against the shoe in the manner above described, and then the tacks will be driven to fasten the device in pressure-applying relation to the upper. It will be observed that the holes 14 are so arranged that 55 the tacks are driven in locations spaced at substantial distances from the edges of the wipers.

After the upper-holding device has been 60 thus applied and fastened to the shoe it will

be left on the shoe until conditions are such that the upper will remain in lasted position without the use of extraneous fastening or holding means, by reason, for example, of the hardening of cement between the upper and 70 the insole or, in the case of box toes, the hardening of the box toe stiffening material. Thereafter the device will be removed from the shoe, preferably by inserting a suitable tool between the bottom of the shoe and the 75 inwardly extending portion 12 of the device and prying it away from the shoe bottom so as to pull the tacks out of the last and the insole.

It will be thus seen that the invention provides upper-holding means of such construction as to render it especially effective in pressing the upper firmly and evenly upon the insole at or near the edge of the shoe bottom, and also a device adapted to be readily applied to the shoe and fastened in operative position and thereafter readily removed from the shoe.

A different form of device for a similar purpose is disclosed in a copending application, Serial No. 494,152, filed on November 7, 1930 as a division of another copending application Serial No. 332,156, filed on January 12, 1929 in which is claimed a method involving the use of such a device; and all claims to 90 subject-matter common to the disclosures of said copending applications and this application are made in the copending applications.

Having described the invention, what I claim as new and desire to secure by Letters 100 Patent of the United States is:

1. Means for holding shoe uppers in lasted position comprising a device adapted to be positioned over the bottom of a shoe on a last and having a portion formed for substantially 105 continuous engagement with the upper along the edge of that portion of the shoe bottom where the device is located to press the upper toward the bottom face of the last, said device having another portion arranged to extend farther inwardly from the edge of the shoe bottom than its upper-pressing portion for use in holding the device on the shoe and offset relatively to said upper-pressing portion to position it in spaced relation to the 110 shoe bottom.

2. Means for holding shoe uppers in lasted position comprising a device adapted to be positioned over the bottom of a shoe on a last and having a portion formed for substantially 120 continuous engagement with the upper along the edge of that portion of the shoe bottom where the device is located to press the upper toward the bottom face of the last, said device having another portion arranged to extend farther inwardly from the edge of the shoe bottom than its upper-pressing portion and offset relatively to said upper-pressing portion to position it in spaced relation to the 125 shoe bottom, said inwardly extending portion 130

- of the device being formed to cooperate with fastening means applied in such relation thereto as to clamp the device down upon the shoe bottom.
5. Means for holding shoe uppers in lasted position comprising a device having a portion formed for holding engagement with an upper on the bottom of a shoe and another portion arranged to extend farther inwardly over the shoe bottom than its upper-holding portion and offset relatively to said upper-holding portion to position it in spaced relation to the shoe bottom, said inwardly extending portion of the device being so formed as 10 to adapt it to be fastened to the shoe by fastening means penetrating the shoe bottom.
6. Means for holding shoe uppers in lasted position comprising a device having a portion formed for holding engagement with an upper on the bottom of a shoe and another portion arranged to extend farther inwardly over the shoe bottom than its upper-holding portion and offset relatively to said upper-holding portion to position it in spaced relation to the shoe bottom, said inwardly extending portion of the device having openings therein arranged to receive fastenings driven into the shoe bottom to fasten the device to the shoe.
- 15 7. Means for holding shoe uppers in lasted position comprising a device adapted to be positioned over the bottom of a shoe on a last and having a portion formed to press the upper toward the bottom of the last upon the outer face of an insole on the last and another portion arranged to extend farther inwardly over the shoe bottom than its upper-pressing portion and offset relatively to said upper-pressing portion to position it out of pressure-applying relation to the shoe bottom, the 20 inwardly extending portion of said device being formed to receive fastening means applied in clamping relation thereto and extending through the insole into the last to hold the upper-pressing portion of the device pressed down upon the shoe bottom.
- 25 8. Means for holding shoe uppers in lasted position comprising a device adapted to be positioned over the bottom of a shoe on a last and having a portion formed for substantially continuous engagement with the upper along the edge of that portion of the shoe bottom where the device is located and arranged to press the upper toward the bottom face of the last only in a location spaced a substantial distance from the edge of the upper, said device having another portion arranged to extend farther inwardly over the shoe bottom than its upper-pressing portion and formed to cooperate with fastening means applied in such relation thereto as to hold the device 30 pressed down upon the shoe bottom.
- 35 9. Means for holding shoe uppers in lasted position comprising a device adapted to be positioned over the bottom of a shoe on a last and having a portion formed for substantially continuous engagement with the upper along the edge of that portion of the shoe bottom where the device is located and arranged to press the upper toward the bottom face of the last only in a location spaced a substantial distance from the edge of the upper, said device having another portion arranged to extend farther inwardly over the shoe bottom than its upper-pressing portion and provided with openings arranged to receive fastenings 40 driven into the shoe bottom to fasten the device in pressure-applying relation to the upper.
- 45 10. Means for holding shoe uppers in lasted position comprising a device adapted to be positioned over the bottom of a shoe on a last and formed to press the upper toward the bottom of the last over an area extending a substantial distance inwardly from the edge of the shoe bottom but terminating at a distance from the edge of the upper, said device being formed for attachment to the shoe farther inwardly from the edge of the shoe bottom than its upper-pressing portion.
- 50 11. Means for holding shoe uppers in lasted position comprising a device adapted to be positioned over the bottom of a shoe on a last and formed to press the upper toward the bottom of the last over an area extending a substantial distance inwardly from the edge of the shoe bottom but terminating at a distance from the edge of the upper, said device having a portion arranged to extend inwardly over the shoe bottom beyond its upper-pressing portion in spaced relation to the shoe bottom and formed to cooperate with fastening means penetrating the shoe bottom to hold the device in pressure-applying relation to the upper.
- 55 12. Means for holding shoe uppers in lasted position comprising a device formed for holding engagement with an upper in the angle between the feather and the lip of an insole, said device being constructed for attachment to the shoe farther inwardly from the edge of the insole than the lip.
- 60 13. Means for holding shoe uppers in lasted position comprising a device formed for holding engagement with an upper in the angle between the feather and the lip of an insole and also formed to extend inwardly

over the insole beyond the lip, said device being constructed to cooperate with means engaging it farther inwardly than the lip to hold it pressed down toward the feather of the insole.

13. Means for holding shoe uppers in lasted position comprising a device having a portion formed for holding engagement with an upper in the angle between the feather and the lip of an insole and another portion arranged to extend inwardly over the lip and offset relatively to said upper-holding portion to clear the lip, said inwardly extending portion of the device being formed to receive fastening means applied in clamping relation thereto to hold the device on the shoe.

14. Means for holding shoe uppers in lasted position comprising a device formed for holding engagement with an upper in the angle between the feather and the lip of an insole and also formed to extend inwardly over the lip and over a portion of the insole beyond the lip, said inwardly extending portion of the device being so constructed as to adapt it to be fastened to the shoe by fastening means penetrating the insole.

15. Means for holding shoe uppers in lasted position comprising a device having a portion formed for holding engagement with an upper in the angle between the feather and the lip of an insole and another portion arranged to extend inwardly over and beyond the lip and offset relatively to said upper-holding portion to clear the lip, said inwardly extending portion of the device having openings therein arranged to receive fastenings driven into the shoe bottom to fasten the device to the shoe.

16. Means for holding shoe uppers in lasted position comprising a device formed for holding engagement with an upper on the bottom of a shoe, said device having openings therein arranged to receive fastenings driven into the shoe bottom to fasten the device to the shoe and being so formed as to determine the position in relation to said openings of a tool for driving the fastenings.

17. Means for holding shoe uppers in lasted position comprising a device formed for holding engagement with an upper on the bottom of a shoe, said device having holes therein arranged to receive tacks driven into the shoe bottom to fasten the device to the shoe and having depressions adjacent to said holes formed to receive and position the nozzle of a tacker for driving the tacks.

18. Means for holding shoe uppers in lasted position comprising a device having a portion formed for holding engagement with an upper on the bottom of a shoe and another portion arranged to extend farther inwardly over the shoe bottom than its upper-holding portion and offset relatively to said upper-holding portion to position it in spaced relation to the shoe bottom, said inwardly ex-

tending portion of the device having holes therein arranged to receive headed fastenings penetrating the shoe bottom to fasten the device to the shoe and having depressions adjacent to said holes formed to receive the heads of the fastenings to position them in closer relation to the shoe bottom.

19. Means for holding the toe portions of shoe uppers in lasted position comprising a device adapted to be positioned over the bottom of a shoe on a last and having a marginal portion curved similarly to the edge of the toe end of the shoe bottom and formed for substantially continuous engagement with the upper around the toe to press the upper toward the bottom face of the last, said device having another portion arranged to extend farther inwardly from the edge of the shoe bottom than its upper-pressing portion for use in fastening the device to the shoe and offset relatively to said upper-pressing portion to position it in spaced relation to the shoe bottom.

20. Means for holding the toe portions of shoe uppers in lasted position comprising a device adapted to be positioned over the bottom of a shoe and having a portion curved similarly to the edge of the toe end of the shoe bottom for holding engagement with the upper around the toe and another portion arranged to extend farther inwardly over the shoe bottom than its upper-holding portion and offset relatively to said upper-holding portion to position it in spaced relation to the shoe bottom, said inwardly extending portion of the device being so formed as to adapt it to be fastened to the shoe by fastening means penetrating the shoe bottom.

21. Means for holding the toe portions of shoe uppers in lasted position comprising a device adapted to be positioned over the bottom of a shoe on a last and having a portion curved similarly to the edge of the toe end of the shoe bottom for pressing the upper about the toe upon the outer face of an insole and another portion arranged to extend farther inwardly over the shoe bottom than its upper-pressing portion and offset relatively to said upper-pressing portion to position it out of pressure-applying relation to the shoe bottom, the inwardly extending portion of the device having one or more openings therein arranged to receive means for fastening it to the last through the insole to hold the upper-pressing portion of the device in pressure-applying relation to the upper.

22. Means for holding the toe portions of shoe uppers in lasted position comprising a plate adapted to be positioned over the bottom of a shoe and having a marginal portion curved to extend around the toe end of the shoe bottom and formed to apply to the upper pressure over an area extending a substantial distance inwardly from the edge of the shoe bottom, said plate having another

- portion upraised from said marginal portion and arranged to extend inwardly over the shoe bottom beyond said marginal portion, said upraised portion being formed to cooperate with fastening means applied to fasten the plate to the shoe.
23. Means for holding the toe portions of shoe uppers in lasted position comprising a plate adapted to be positioned over the bottom of a shoe and having a marginal portion curved to extend around the toe end of the shoe bottom and formed to apply to the upper pressure over an area extending a substantial distance inwardly from the edge of the shoe bottom, said plate having another portion upraised from said marginal portion and arranged to extend inwardly over the shoe bottom beyond said marginal portion, said inwardly extending portion of the plate having holes therein arranged to receive tacks driven into the shoe bottom to fasten the plate in pressure applying relation to the upper.
24. Means for holding the toe portions of shoe uppers in lasted position comprising a device adapted to be positioned over the bottom of a shoe on a last and formed for substantially continuous engagement with the upper around the toe to press it toward the bottom of the last over an area terminating at a substantial distance from the edge of the upper, said device being formed for attachment to the shoe farther inwardly from the edge of the shoe bottom than its upper-pressing portion.
25. Means for holding the toe portions of shoe uppers in lasted position comprising a device adapted to be positioned over the bottom of a shoe on a last and formed for substantially continuous engagement with the upper around the toe to press it toward the bottom of the last over an area terminating at a substantial distance from the edge of the upper, said device being formed to extend inwardly over the shoe bottom beyond its upper pressing portion and having in its inwardly extending portion openings adapted to receive fastenings driven into the shoe bottom to fasten it to the shoe.
26. Means for holding the toe portions of shoe uppers in lasted position comprising a device adapted to be positioned over the bottom of a shoe on a last and formed to press the upper around the toe toward the bottom of the last over an area extending a substantial distance inwardly from the edge of the shoe bottom but terminating at a distance from the edge of the upper, said device being constructed to cooperate with means engaging it farther inwardly from the edge of the shoe bottom than its upper-pressing portion to hold it in pressure applying relation to the upper.
27. Means for holding the toe portions of shoe uppers in lasted position comprising a device adapted to be positioned over the bot-
- tom of a shoe on a last and formed to press the upper around the toe toward the bottom of the last over an area extending a substantial distance inwardly from the edge of the shoe bottom but terminating at a distance from the edge of the upper, said device having a portion arranged to extend inwardly over the shoe bottom beyond its upper-pressing portion and formed to cooperate with fastening means penetrating the shoe bottom to hold the device in pressure-applying relation to the upper.
28. Means for holding the toe portions of shoe uppers in lasted position comprising a device adapted to be positioned over the bottom of a shoe on a last and having a portion curved similarly to the edge of the toe end of the shoe bottom and formed for substantially continuous engagement with the upper around the end and along the sides of the toe to press the upper toward the bottom of the last only in a location spaced a substantial distance from the edge of the upper, said device having another portion arranged to extend farther inwardly over the shoe bottom than its upper-pressing portion and arranged relatively to said upper-pressing portion to position it in spaced relation to the shoe bottom, said inwardly extending portion of the device being constructed to cooperate with means applied to fasten the device to the shoe in pressure-applying relation to the upper.
29. Means for holding the toe portions of shoe uppers in lasted position comprising a device adapted to be positioned over the bottom of a shoe on a last and having a portion curved similarly to the edge of the toe end of the shoe bottom for pressing the upper about the toe upon the outer face of an insole and another portion arranged to extend farther inwardly over the shoe bottom than its upper-pressing portion and offset relatively to said upper-pressing portion to position it out of pressure-applying relation to the shoe bottom, said inwardly extending portion of the device having a row of holes therein arranged to receive fastenings driven through the insole and into the last near the end and the sides of the toe to fasten the device in pressure-applying relation to the upper.
30. Means for holding the toe portions of shoe uppers in lasted position comprising a device adapted to be positioned over the bottom of a shoe on a last and having a portion curved similarly to the edge of the toe end of the shoe bottom for pressing the upper about the toe upon the outer face of an insole and another portion arranged to extend farther inwardly over the shoe bottom than its upper-pressing portion and offset relatively to said upper-pressing portion to position it out of pressure-applying relation to the shoe bottom, said inwardly extending portion of the device having holes therein arranged to

receive tacks driven into the shoe bottom to fasten the device to the shoe and having depressions adjacent to said holes formed to receive and position the nozzle of a tacker for driving the tacks.

31. Means for holding the toe portions of shoe uppers in lasted position comprising a plate adapted to be positioned over the bottom of a shoe in engagement with the upper around the toe end of the shoe bottom, said plate having a plurality of holes therein arranged to receive tacks driven into the shoe bottom to fasten the device to the shoe and being so constructed as to determine the position of the nozzle of a tacker in relation to each hole for driving the tack.

32. Means for holding the toe portions of shoe uppers in lasted position comprising a device adapted to be positioned over the bottom of a shoe in holding engagement with the upper around the toe end of the shoe bottom and having surfaces arranged to be engaged by the toe wipers of a lasting machine to press the device both inwardly over the shoe bottom and downwardly upon the shoe bottom simultaneously, said device having a portion arranged to extend farther inwardly from the edge of the shoe bottom than its upper-holding portion and formed to cooperate with fastening means applied in clamping relation thereto to fasten the device to the shoe.

33. Means for holding the toe portions of shoe uppers in lasted position comprising a device adapted to be positioned over the bottom of a shoe in holding engagement with the upper around the toe end of the shoe bottom and having surfaces arranged to be engaged by the toe wipers of a lasting machine to press the device both inwardly over the shoe bottom and downwardly upon the shoe bottom simultaneously, said device having a portion arranged to extend farther inwardly from the edge of the shoe bottom than its upper-holding portion and formed to cooperate with fastening means penetrating the shoe bottom to hold the device in pressure-applying relation to the upper.

34. Means for holding the toe portions of shoe uppers in lasted position comprising a device adapted to be positioned over the bottom of a shoe in holding engagement with the upper around the toe end of the shoe bottom and having surfaces arranged to be engaged by the toe wipers of a lasting machine to press the device both inwardly over the shoe bottom and downwardly upon the shoe bottom, said device having a portion arranged to extend inwardly over the shoe bottom beyond the edges of the wipers and having in said inwardly extending portion a plurality of openings spaced at substantial distances from the edges of the wipers to receive fastenings driven into the shoe bottom for fastening the device to the shoe.

35. Means for holding the toe portions of shoe uppers in lasted position comprising a device adapted to be positioned over the bottom of a shoe on a last in engagement with the upper around the toe end of the shoe bottom to press the upper upon the outer face of an insole and having a portion arranged to extend farther inwardly over the shoe bottom than its upper-pressing portion and offset relatively to said upper-pressing portion to position it in spaced relation to the shoe bottom, said device having surfaces arranged to be engaged by the toe wipers of a lasting machine to press the device both inwardly over the shoe bottom and downwardly upon the shoe bottom, and said inwardly extending portion of the device having one or more openings therein to receive fastening means penetrating the shoe bottom to fasten the device to the shoe in pressure-applying relation to the upper.

36. Means for holding the toe portions of shoe uppers in lasted position comprising a device adapted to be positioned over the bottom of a shoe on a last and having a portion curved similarly to the edge of the toe end of the shoe bottom for pressing the upper about the toe upon the outer face of an insole and another portion arranged to extend farther inwardly over the shoe bottom than its upper-pressing portion and offset relatively to said upper-pressing portion to position it out of pressure-applying relation to the shoe bottom, the different portions of said device being so arranged relatively to each other as to provide surfaces adapted to be engaged by the toe wipers of a lasting machine to press the device both inwardly over the shoe bottom and downwardly upon the shoe bottom and the inwardly extending portion of the device having therein a plurality of holes arranged to receive fastenings driven into the shoe bottom to fasten the device to the shoe.

37. Means for holding the toe portions of shoe uppers in lasted position comprising a device having a marginal portion curved similarly to the edge of the toe end of the shoe bottom for holding engagement with the upper in the angle between the feather and the lip of an insole around the toe and having another portion arranged to extend inwardly over the lip for use in fastening the device to the shoe and offset relatively to said upper-holding portion to clear the lip.

38. Means for holding the toe portions of shoe uppers in lasted position comprising a device having a marginal portion curved similarly to the edge of the toe end of the shoe bottom for holding engagement with the upper in the angle between the feather and the lip of an insole around the toe, said device having another portion arranged to extend inwardly over the insole beyond the lip and arranged relatively to said upper-

holding portion to clear the lip, said inwardly extending portion being formed to co-operate with means for clamping the device down upon the shoe bottom.

5 39. Means for holding the toe portions of shoe uppers in lasted position comprising a device having a marginal portion curved similarly to the edge of the toe end of the shoe bottom for holding engagement with

10 the upper in the angle between the feather and the lip of an insole around the toe, said device having another portion arranged to extend inwardly over the shoe bottom beyond the lip and formed for attachment to the

15 shoe by fastenings driven into the shoe bottom.

40. Means for holding the toe portions of shoe uppers in lasted position comprising a plate having a marginal portion curved similarly to the edge of the toe end of the shoe bottom for holding engagement with the

20 upper in the angle between the feather and the lip of an insole around the toe and having another portion upraised from said marginal

25 portion and arranged to extend inwardly over the insole beyond the lip, said inwardly extending portion of the plate having holes therein arranged to receive fastenings driven into the shoe bottom to fasten the device to

30 the shoe.

In testimony whereof I have signed my name to this specification.
